US00D578170S

(12) **United States Design Patent**
Chiang et al.

(10) **Patent No.:** US D578,170 S
(45) **Date of Patent:** ** Oct. 7, 2008

(54) **ROBOT TOY**

(75) Inventors: **Tsu-Li Chiang**, Shenzhen (CN);
Chuan-Hong Wang, Shenzhen (CN);
Kun-Chih Hsieh, Shenzhen (CN);
Kuan-Hong Hsieh, Shenzhen (CN)

(73) Assignees: **Ensky Technology (Shenzhen) Co., Ltd.**, Baoan District, Shenzhen, Guangdong Province (CN); **Ensky Technology Co., Ltd.**, Pan Chiao, Taipei Hsien (TW)

(**) Term: **14 Years**

(21) Appl. No.: **29/299,618**

(22) Filed: **Dec. 31, 2007**

(30) **Foreign Application Priority Data**

Jul. 4, 2007 (CN) 2007 3 0170944

(51) **LOC (8) Cl.** 21-01

(52) **U.S. Cl.** D21/578

(58) **Field of Classification Search** D21/578-583,
D21/621, 622; 446/268, 384

See application file for complete search history.
